UNITED STATES PATENT OFFICE.

JAMES HARTNESS, OF SPRINGFIELD, VERMONT.

CHUCK.

1,082,590.

Specification of Letters Patent. Patented Dec. 30, 1913.

Application filed February 20, 1913. Serial No. 749,631.

To all whom it may concern:

Be it known that I, JAMES HARTNESS, a citizen of the United States, and a resident of Springfield, in the county of Windsor and State of Vermont, have invented certain new and useful Improvements in Chucks, of which the following is a specification.

This invention has relation to chucks and 10 more particularly to "scroll" chucks, so-called, in which the radially movable jaws are moved in guideways in the body of the chuck by a scroll engaging one or more teeth or projections in the rear portions of the 15 jaws.

The invention consists in constructing the body in sections so spaced apart as to form 20 equally spaced guideways for the jaws. These sections are approximately sector-shaped and may be adjusted so as to provide for a varying number of jaws, so that, 25 if desired, a chuck may be equipped with three jaws or with four jaws according to the character of the work to be operated on, or according to the desire of the operator.

In furnishing a chuck, there are provided a plurality of body sections and a plurality of spacers. The sections are made in pairs and each section of the pair is formed on 30 its outer side to constitute one wall of a guideway for the jaw, so that, when two adjacent sections of two pairs are properly placed and spaced apart, they form a guideway between them in which the jaw may be 35 operated by the scroll.

Referring to the accompanying drawings, Figure 1 represents a front elevation of a chuck embodying the invention, provided with four jaws. Fig. 2 represents a section 40 on the line 2-2 of Fig. 1. Fig. 3 represents a side elevation of the chuck. Fig. 4 represents a section on the line 4-4 of Fig. 1. Fig. 5 represents a section on the line 5-5 of Fig. 1. Fig. 6 shows one of the 45 body sections detached. Fig. 7 represents a front elevation of the same chuck arranged to receive three jaws. Fig. 8 represents a section on the line 8-8 of Fig. 7. Fig. 9 shows a front elevation of the chuck with 50 the body removed. Fig. 10 represents a section on the line 10-10 of Fig. 8. Fig. 11 represents a side elevation of the chuck. Fig. 12 represents one of the spacers detached.

55 Referring to the drawings,--20 indicates the back-plate of the chuck which is formed

with a hub 21 internally threaded so as to screw upon the end of a hollow spindle 22. This back-plate might, if desired, be formed integrally with the spindle. In the face of 60 the back-plate, there is an annular groove 23 to receive the jaw-operating scroll 24. Loosely mounted on the hub 21 of the back-plate, there is a gear-operating scroll 25 having a rearwardly extending marginal 65 flange 26 formed by cutting a groove 27. A clamp-brake, such as illustrated in my co-pending application Serial No. 722,962, filed September 28, 1912, may be used to clamp the flange 26 and hold the scroll 25 against 70 rotation. Preferably the back-plate and the rear scroll 25 are equal in external diameter. The back-plate 20 serves as a support for one or more spiral gears 28 (see Fig. 75 9). The axes of these gears are tangential to a circle circumscribed about the axis of the back-plate and they are preferably equidistant as shown. The said gears are loosely mounted on smooth portions of screw pins 29 which are passed into sockets formed in 80 the back-plate, the gears themselves being located in recesses extending through the web of the back-plate as shown in Fig. 5. The arrangement of the gears is such that they intermesh with the scroll teeth 30 85 formed on the front face of the rear scroll 25, and also intermesh with rack teeth 31 formed on the rear face of the jaw-operating scroll 24. When the chuck is quiescent, the rotation of the rear scroll causes the rotation 90 of the jaw-operating scroll (and the actuation of the jaws) through the medium of the interposed power-transmitting mechanism, which in this case consists of one or more of the spiral gears 28. When the 95 chuck is in rotation, the rear scroll may be retarded so as to cause a similar movement of the jaw-operating scroll. Ordinarily the back-plate and the scroll 25 rotate in unison. The rear scroll is held against axial 100 movement by a collar 32 detachably secured by any suitable means such as a screw 33 and pin 34 to the hub 21 of the back-plate. In general, the parts which I have described correspond to those which are illustrated in 105 my application to which I have previously made reference.

The body of the chuck in the present case consists of a plurality of sections which may be located in various positions to form 110 guideways for various numbers of jaws. In Fig. 1, there are four jaws which are

indicated at 40, 41, 42 and 43. In this case, the jaws are arranged in perpendicularly intersecting lines and form an angle of 90° between two adjacent jaws. In Fig. 7, the 5 jaw 43 is omitted and said jaws are arranged so that two adjacent jaws form an angle of 120° . The jaws are provided with teeth or projections on their rear faces to engage the jaw-engaging scroll, and on their 10 front portions they are formed with the usual shoulders as shown in Figs. 2 and 8. The parallel side faces of each jaw are formed with tongues and grooves as shown in Figs. 3, 4 and 11. 15 In Fig. 1, the body of the chuck is shown as comprising eight sections *a*, *b*, *c*, *d*, *e*, *f*, *g* and *h*. They are arranged in pairs *a b*, *c d*, etc., the inner faces of the sections of each pair abutting and the outer faces of the sections of each pair being provided with tongues and grooves complementary to those formed in the jaws. In Fig. 1, the four pairs of sections are arranged to provide for radial grooves to receive the four jaws. 20 Each section is secured to the rear plate by a plurality of screws or like fastenings. Viewed in front elevation, the screws are arranged in two circles, one series of screws being located near the outer margins of the 25 sections and the other screws being located near their inner ends. There are two of the outer screws 44 and one inner screw 45 for each section. For the purpose of enabling an adjustment of the sections to provide for 30 a smaller number of jaws, I furnish with each chuck a plurality of spacers *k*, of which one is shown in Fig. 12. Each spacer is adapted to be placed between the sections of a pair of sections so as to spread them 35 apart. The side faces of each spacer are at approximately an angle of 30° , so that, when a spacer is placed between the sections of a pair, the outer faces of the pair will be 40 changed from an angle of 90° to an angle of 45 120° , thus making provision for the employment of only three jaws instead of four. For the purpose of changing over the chuck from four jaws to three jaws, all of the sections shown in Fig. 1 are removed except 50 those indicated at *a* and *h*. Then two spacers *k* are secured in place adjacent the remaining sections *a* and *h*. Then the two sections *b* and *g* are next secured in place in the positions shown in Fig. 7. The sections 55 *c* and *d*, with the spacer *k* between them, are then secured to the back-plate, so that as a result three radial guideways are provided for the three jaws 40, 41 and 42. Thus the two sections *e f* and the jaw 43 are temporarily laid aside until it is desired to 60 transform the chuck again into a four-jawed chuck. The back-plate is provided with a proper number of properly spaced apertures to receive the fastening screws 44 and 45 65 for the sections and also with apertures to

receive fastening screws 46 and 47 which secure the spacers to the back-plate.

So far as I am aware, I am the first to have provided a chuck comprising a back-plate and a body formed of a plurality of sections adjustable to form a varying number of guideways for the jaws. I might, of course, omit the section spacers altogether, but I prefer to use them as they stiffen the body and hold the sections of each pair rigidly in their proper positions. 75

Having thus explained the nature of my said invention and described a way of making and using the same, although without attempting to set forth all of the forms in which it may be made or all of the modes of its use, what I claim is:

1. A scroll chuck comprising a jaw-operating scroll, a plurality of radial jaws, a back-plate, and a body consisting of a plurality of sections secured to said back-plate, said sections being spaced to form guideways for said jaws. 80

2. A scroll chuck comprising a plurality of radial jaws, a jaw-operating scroll, a back-plate, and a body attached to the back-plate and consisting of a plurality of pairs of sections, said pairs being separated to form guideways for the jaws. 90

3. A scroll chuck comprising a plurality of radial jaws, a jaw-operating scroll, a back-plate, and a body attached to the back-plate and consisting of a plurality of sections, said sections being adjustable to provide a varying number of equally spaced guideways for receiving an equal number of jaws. 95

4. A scroll chuck comprising a jaw-operating scroll, and a back-plate, of a plurality of radial jaws, and a detachable body, said body consisting of a plurality of pairs of sections separated to form guideways for the jaws, and secured independently of each other to the back-plate. 105

5. A chuck comprising a back-plate, jaw-operating mechanism, a plurality of jaws, a body consisting of a plurality of adjustable sector-shaped sections spaced to form guideways for the jaws, said back-plate having provisions for receiving a variable number of sections to accommodate a variable number of jaws. 110

6. A chuck comprising a back-plate, jaw-operating mechanism, and a body consisting of a series of independent sections spaced to form radial guideways for the jaws, said sections being adapted to be adjusted to vary the number of such guideways, and means for securing said sections to the back-plate in the positions to which they may be adjusted. 120

7. A chuck comprising a back-plate and a sectional body detachably secured thereto, the sections being adapted to be equally spaced in different positions to receive either three or four jaws. 125

8. A chuck comprising a back-plate, a jaw-operating scroll, and a body consisting of a series of pairs of detachable sector-shaped sections spaced apart to form radial 5 jaw-receiving guideways, and a sector-shaped spacer between the sections of each pair, said spacers being removable, the sections of said pair being adapted to be closed together, and said pairs to be adjusted,

whereby space is made for an additional 10 pair of sections, and for an additional guideway for an additional jaw.

In testimony whereof I have affixed my signature, in presence of two witnesses.

JAMES HARTNESS.
